UNITED STATES PATENT OFFICE

2,592,465

ROOF

Henri Maclaine Pont, The Hague, Netherlands

Application July 8, 1947, Serial No. 759,585
In the Netherlands March 5, 1941Section 1, Public Law 690, August 8, 1946
Patent expires March 5, 1961

2 Claims. (Cl. 108—1)

1

The invention relates to a roof, which, as for instance in a saddle roof or like construction, is supported by spaced apart gables and/or roof trusses or, as for instance in a dome-shaped roof or a broach roof, is supported by corner ribs or principal rafters meeting in a top. It has for its object to avoid the usual roofing lath work, series of boom members, layers of joists, partitions or boarding and like rigid, heavy, many abutments requiring constructions for the support of the roof covering, such as tiles, slates, roofing sheet iron, reinforced roofing leather and like covering means, and to replace them by a very light and strong construction, which is particularly appropriate for large spans and can be made in a simple and cheap way without or nearly without the aid of standing or hanging scaffolding means.

According to the invention this object is attained by a construction, which substantially consists of a network of wires, tapes or cables stretched between the rigid supporting members referred to, such as gables, roof trusses, corner ribs and rafters or rafter principals, the ridge, if present, and the roof eaves, and of a normal roof covering directly supported by said network. Such a network is not, as the roofing frame in rigid constructions is, subjected to bending stresses but is only subjected to the action of tensile forces, since it is composed of almost completely flexible members. Therefore it can be loaded much heavier, that means, it can be used for much larger spans.

Preferably the network consists of purlin-wires and rafter-wires, said wires being interconnected at their crossings so as to protect them from mutual displacement. A practical connection is obtained, when, at their crossings, the purlin-wires and the rafter-wires engage each other with U-shaped bends, and an annular member, for instance a helicoidally wound wire, is mounted round each of said crossings. This manner of interconnecting the wires of the network makes it possible to weave the network one wire after the other between the rigid or semi-rigid supporting members after the erection of the latter. To that end wires are used, in which, at predetermined distances corresponding to the dimensions of the roof covering parts, said U-shaped bends are made beforehand by hand or a rolling operation. Weaving the network one wire after the other in the roofing planes themselves has the advantage that no large ground area for the prefabrication of the networks is required, which often are very large, further that heavy networks

2

need not be hoisted, the tightening of the networks is much easier and deformation of the networks by tensioning it in an oblique direction can be avoided in an easier way.

5 The mounting of the rings at the crossings can be facilitated with the aid of a so-called tightener, by means of which the crossing wires can be spaced apart at each crossing as far as is allowed by the bends. At the same time the 10 wires of the network can be tightened by said tightener.

In order to reinforce the network wires may be provided, which according to the invention lie in the plane of the network but on the lower 15 surface thereof, extend in an oblique direction with respect to the purlin-wires and the rafter-wires, and prevent the construction, when intended for a dome-shaped roof or a broach-roof, from torsion.

20 For the elucidation of the invention reference is had to the drawing, which illustrates by way of example an embodiment of the invention in diagram; in the drawing:

Fig. 1 is a plan view of a part of a dome-shaped roof of large span during the construction thereof,

Fig. 2 is, in diagram, a sectional view on line II—II of Fig. 1,

Fig. 3 is, on an enlarged scale, a part of a network, in which a tightener is placed, and

30 Fig. 4 is a crossing or point of junction of the network according to Fig. 3 together with a tightener of other construction.

In Figs. 1 and 2 numeral 1 designates corner 35 ribs or rafters or rafter principals placed in a hexagon and meeting in a top 2. These principals span a certain space to be roofed and rest on supporting posts 3, which slant to the outside. Near their bearing surfaces the rafter principals 1 are interconnected by eaves-cables 4. Networks of iron or steel wire are stretched between said principals 1 and the eaves-cables 4. These networks consist of rafter-wires 5 extending in the roofing plane from the eaves-cable upwards and of purlin-wires 6, which follow the horizontal line of tension, while retaining the natural sag. The rafter-wires 5 and the purlin-wires 6 may, as is shown in Figs. 3 and 4, be provided with U-shaped bends 7 and 8 at 45 uniform distances and engage each other with said bends at their crossings or intersecting points, so that they are prevented from displacement with respect to one another at the crossings. In order that the wires remain in engagement with one another at their crossings after 50 55

the provision of the roof covering, a ring 9 is provided round the bends engaging each other, said ring being, in the manner of a key-ring, constituted of a helicoidally wound wire. In order that the ring can be easily mounted and the network can be tightened a tightener is used, which consists of a U-shaped rod 10 and an individual bar 11, on which the bent rod 10 comes to rest after being thrust with both legs under one of the wires at the crossing. In Fig. 4 the tightener is formed as a fork 12 having a bar 13 hinged thereto. The tightener according to Fig. 4 is suitable for heavier work, for instance for networks of steel wire and for very large spans.

The network can be completely prefabricated and then be stretched between the edges of the roofing planes. It has been found that it is simpler and gives better results, when the network is woven one wire after the other in the roofing plane. In that case, the U-shaped bends preferably are made in the wires beforehand. In order to obtain a taut and uniform network the following method may be carried out:

After the erection of the rafter principals 1 and the provision of the eaves-cables 4 first the middlemost rafter-wires are stretched from the top 2 to the middle of the eaves-cables 4. By means of their U-shaped bends these rafter-wires indicate the places in which the purlin-wires must be provided. These main rafter-wires serve, as it were, as ordinate of the network. Thereupon the first purlin-wire is stretched near each eaves-cables 4, said wire acting by its U-shaped bends as abscissa. Then, guiding rafter-wires may be attached to the eaves-cables at distances of one-quarter, one eighth, one sixteenth, etc. of said cables and with their upper ends provisionally but firmly secured to the rafter principals (the ridge line or the ridge beam). These guiding rafter-wires are interconnected by a loose purlin-wire at their upper ends. By that fact the eaves-cable is pulled up in an inclined direction and soon assumes almost, although in the shape of a polygon, the definite curve. Thereupon, starting from below, the purlin-wires and, at the ends of these wires, that means in the corners between the rafter principals and the eaves-cables, and also on both sides of the guiding rafter-wires, the rafter-wires may be provided over areas, which are within easy reach of the workmen standing on the eaves-cable. While working the workmen may come up to each other.

After the bends of the rafter-wires and the purlin-wires have been interconnected at the crossings thereof and the connections have been fixed by the mentioned rings, in said corners and on both sides of the guiding rafter-wires a network is obtained over an area within reach, which can be safely climbed and from which further parts of the network can be completed.

In that case the work is done uniformly from bottom to top without the aid of any scaffolding means. It will be obvious that all roofing planes must be treated simultaneously and at the same pace. The purlin-wires and the rafter-wires are definitely secured to the rafter principals (or the ridge) as the network gets completed from bottom to top over the entire breadth.

Anti-torsion wires or bracings 14 may be stretched below the network for dome-shaped roofs or broach roofs. These bracings may have

an oblique direction with respect to the purlin- and the rafter-wires; they may be attached in certain places to the crossings of the network by pieces of wire and are adapted to take up a part of the roofing load.

After all wires of the network have been provided, the provisionally attached wires thereof have been definitely secured and the anti-torsional bracings, if necessary, have been tightened, the roof covering can be provided.

In roofs having a ridge, for instance in saddle roofs, the rafter wires are stretched between a ridge-line and the eaves-cables and the purlin-wires are stretched between the edges of the sables or between roof trusses.

What I claim is:

1. In a roof of large span comprising, in combination, abutment structures disposed at the corners of the space to be roofed, curved rafters 20 mounted on one of their ends on the abutment structures and having their opposing ends inclined upwardly and connected together, the rafters having their concave sides facing inwardly, eaves-cables provided around the roof space and connected to the abutment structures, networks mounted on the rafters and including crossed wires having interengaging U-shaped bends formed at their crossed points, an annular member formed by a helically wound wire provided around each of the interengaging bends, said networks being disposed in the roofing planes between the rafters and the eaves-cables and keeping the latter bent upwards, said roofing networks being adapted to directly support a roof covering, said rafters, said eaves-cables and said roofing networks defining a balanced umbrella structure.
2. In a large span roof having abutment structures at the corners of the space, to be roofed, 40 arcuate rafters mounted at one end on the abutment structures, said rafters being disposed in an inclined plane and joined together at their other ends to define the top of the roof, said rafters being disposed with their convex sides disposed upwardly and eaves-cables connecting the lower ends of the rafters and provided around the roofed space, the improvement which consists of networks mounted on the rafters and comprising crossed wires having mating U-shaped bends formed at their crossings, and a locking member connecting the mating bends together, said networks being provided in the roofing planes between the rafters and said eaves-cables and retaining the eaves-cables bent upwardly and the networks being adapted to support a roof covering.

HENRI MACLAINE PONT.
